UNITED STATES PATENT OFFICE.

FREDERICK G. GRUEN, OF CINCINNATI, OHIO, ASSIGNOR TO THE D. GRUEN SONS & COMPANY, OF CINCINNATI, OHIO, A CORPORATION OF OHIO.

SWIVEL.

1,399,112.

Specification of Letters Patent.

Patented Dec. 6, 1921.

Application filed June 26, 1920. Serial No. 391,978.

To all whom it may concern:

Be it known that I, FREDERICK G. GRUEN, a citizen of the United States of America, and resident of Cincinnati, in the county 5 of Hamilton and State of Ohio, have invented a new and useful Improvement in Swivels, of which the following is a specification.

An object of my invention is to provide 10 a swivel clasp that will have beauty and novelty and will not detract from the pleasing effect made upon the eye by a watch and chain, between which the clasp is interposed.

15 Another object is to eliminate the disagreeable contact made by a clasp interposed between a watch and chain, or when similarly inserted between other objects.

These and other objects are attained by 20 the means described herein and disclosed in the accompanying drawing in which:

Figure 1 is a front view showing in detail a device embodying my invention.

25 Fig. 2 is a side elevation of the device shown in Fig. 1.

My invention comprises a swivel clasp A, such as is ordinarily used to secure a watch to a chain, having a leaf B, or some other ornamental covering mounted upon the body 30 a of the swivel and extending over and attached to one side of the hook a'.

The swivel clasp A is similar to the swivel clasps ordinarily attached to watch chains, fobs, etc., and comprises the body a, hook a', 35 the spring latch a² adapted to normally engage the hook a' and to thereby form a closed loop in which the ring on a watch stem may be inserted, and the swivel head a³ mounted upon the body a and to which a 40 chain, not shown, may be attached.

The leaf, flower, or other ornamental covering B is mounted upon the body a and extends over the hook a', to which it is attached, substantially concealing the hook a' 45 and spring latch a² from the front of the clasp. The leaf B may be made in any form or design and may be formed integral with the body a and hook a' or may be mounted thereupon by any means, for example by

riveting or soldering. The leaf B need not 50 be affixed for its whole length, or even in part, to the hook, or it can be affixed only to the hook and need not extend over the body a, the specific effect desired being the controlling feature, provided the 'affixed 55 ornament covers or causes hook a' to harmonize with the swivel clasp as a whole.

The operation of my device is as follows: Assuming that a lady had a clasp embodying my invention mounted thereon attached 60 to a watch chain such as is ordinarily worn about the neck, she would turn the body a about the swivel head a³ of the clasp until the ornament B is toward the front and away from the wearer, thereby not only effectively concealing from view the unsightly hook a' but adding certain beauty, novelty 65 and charm to the watch and chain attached to the swivel clasp.

What I claim is:

1. As a new article of manufacture the combination with a swivel clasp comprising a body and a hook, of an ornamental covering fixedly mounted upon the body and the hook and substantially obscuring the hook 75 from one side.

2. As a new article of manufacture the combination with a swivel clasp having a hook of an ornamental covering fixedly mounted upon the hook and adapted to 80 substantially conceal the hook from one side.

3. As a new article of manufacture the combination with a swivel clasp having a hook extending along the front of the clasp, of an ornamental covering fixedly mounted 85 on the front of the clasp and adapted to substantially conceal the hook from the front of such clasp.

4. As a new article of manufacture the combination with a swivel clasp comprising 90 a body and a hook extending from the front of the body, of an ornamental covering fixedly mounted upon the front of the body and extending over and being attached to the hook.

In witness whereof, I have hereunto subscribed my name this 24th day of June, 1920.

FREDERICK G. GRUEN.
